(57) **CLAIM**

The ornamental design for a calibration fixture for current probes, as shown and described.

DESCRIPTION

FIG. 1 is a perspective view of the calibration fixture for current probes.

FIG. 2 is a side elevation of the calibration fixture for current probes of FIG. 1.

FIG. 3 is a top plan view of the calibration fixture for current probes of FIG. 1.

FIG. 4 is a bottom plan view of the calibration fixture for current probes of FIG. 1.

FIG. 5 is a perspective view of the calibration fixture for current probes of FIG. 1, having the upper cover removed; and,

FIG. 6 is a sectional view of the calibration fixture for current probes of FIG. 3, taken along line 3-3.

The broken lines in FIGS. 1 and 3 depict optional connection structure and the broken lines of FIG. 6 depict unseen internal structure and are illustrative of environment and not intended to form a part of the claimed design.
